PHONOGRAPH

Clemence R. Raney, Riverside, Ill.

Application January 11, 1934, Serial No. 706,264

90 Claims. (Cl. 274—10)

My invention relates to phonographs.

It has among its objects to provide an improved phonograph and particularly to provide an improved phonograph of the type having a magazine for receiving a series of records to be reproduced and having improved mechanism for reproducing automatically and successively the records in the magazine. Another object of my invention is to provide an improved mechanism of this type, wherein the automatic operations of the mechanism are extended in such manner as to produce a wholly automatic machine and wherein improved means are provided for controlling the automatic functions of the mechanism. A further object is to provide improved and simplified means for starting the automatic operation of the machine by the insertion of one or more records in the magazine irrespective of differences in diameter and automatically stopping the operation of the machine upon completion of the reproduction of the last record in the magazine, all of which is accomplished with a greatly simplified and entirely automatic mechanism. A further object of my invention is to provide an improved control means for the starting and stopping of the phonograph operated by the inserted records as aforesaid and automatically when desired, which also includes a record receiving compartment adapted to receive the reproduced records and has means associated therewith for actuating said control means and automatically interrupting the operation of the phonograph when the compartment becomes full. A still further object of my invention is to provide an automatic phonograph adapted to play records of different size as fed from the magazine regardless of their order therein, the operation of which is automatically controlled by the insertion in the magazine of a record regardless of its size, all without the necessity for adjustment on the part of the operator. Another object is to provide an improved and simplified mechanism operative upon completing the reproduction of the record for returning the reproducer and placing the same in playing position on the edge of the next record to be reproduced. Further objects of my invention are to provide improved means for transferring records from the magazine to the record reproducing table; an improved mechanism which is operated by the inward swing of the reproducer mechanism for controlling the automatic return of the reproducer arm to playing position and which is operative with records of the type having eccentric as well as concentric inner needle grooves; as well as an improved

mechanism operative subsequently to the reproduction of a record for tripping the aforesaid mechanism and having an improved and more positive action. These and other objects and advantages of my improved construction will, however, hereinafter more fully appear.

In the accompanying drawings, I have shown for purposes of illustration, one embodiment which my invention may assume in practice.

In these drawings:

Fig. 1 is a longitudinal sectional view of this embodiment of my invention, certain parts being in section or elevation to facilitate illustration.

Fig. 2 is a plan view of the mechanism shown in Fig. 1, certain of the parts being broken away to facilitate illustration.

Fig. 3 is an end view of the record magazine illustrating the record controlled switch for the machine.

Fig. 4 is an enlarged sectional detail taken on line 4—4 of Fig. 1.

Figs. 5 and 6 are similar details showing the parts in different positions.

Fig. 7 is a sectional detail taken on line 7—7 of Fig. 1.

Fig. 8 is a sectional elevation of the discharged record compartment of Fig. 1, showing the compartment full of records and the operating member of the control switch in switch open position.

Fig. 9 is a diagrammatic showing of the electrical control circuit for the phonograph.

Fig. 10 is an enlarged detail of the off-center record centering pin.

Certain features of the automatic phonograph construction illustrated herein are disclosed and claimed in my copending application, Ser. No. 295,017, filed July 24th, 1928, the present invention consisting in certain improvements over the construction of the aforesaid application.

In the construction illustrated herein, which is of the general type of the above application, a power driven mechanism is operated from an electric motor 1 and includes a record rotating table 2 driven by the motor and a tone arm 3 carrying a reproducer 4 adapted to co-operate with a record on the table 2, means being provided whereby movements of the tone arm are controlled and records are supplied to and discharged from the table automatically in timed relation to the movements of the tone arm, all in a manner especially adapted to use in connection with records of different size and subject to the control of improved controlling mechanism as will hereinafter more fully appear.

Referring first to the general arrangement of

this illustrative construction, which is generally similar to that in my prior application, it will be noted that the table 2 is located directly above the motor 1, and that the reproducer arm 3 and its associated mechanism is adapted to swing laterally relative to the table in a well known manner (Figs. 1 and 2). Improved reproducer controlling mechanism, herein including a drum of the general type disclosed in my application aforesaid, is disposed below the table and above the motor 1. Moreover, co-operating record feeding mechanism herein including a magazine comprising a laterally feeding conveyor mechanism, generally similar to that in my prior application, is disposed to the left of the table, Figs. 1 and 2, and adapted to feed records successively thereon. Improved control mechanism is also provided in connection with the feeding mechanism for automatically controlling the operation of the phonograph in response to the insertion of one or more records in the magazine irrespective of their size and controlled by the presence of records therein. Also, generally similar record discharging mechanism is herein disposed below the table and adapted to discharge the record into a compartment located at the right and below the table and having improved controlling mechanism associated therewith.

Considering more particularly the drive arrangement of the mechanism shown, it will be noted that the electric motor 1 has a vertical shaft 5 which extends upwardly a substantial distance and projects through a horizontal sheet metal base 6 forming what may be called the floor of the mechanism below the table 2. As shown, this base 6 is carried on a horizontal main casting 7 suitably supported on the frame above the motor and is also removably supported on a usual cabinet 8, thus permitting ready access to the mechanism, see particularly Fig. 1. As illustrated, the table 2 is herein fixed to the upper end of the shaft 5 which constitutes a fixed axis for the table, while the power drive for the mechanism is preferably taken off this shaft 5 at a point between the motor and the base 6.

Referring next to the mechanisms driven by shaft 5, we will first consider the reproducer controlling mechanism which is the same as that in my prior application. As shown, a worm 9 on the shaft 5 meshes with a worm gear 12 which is rotatable on a transverse horizontal axis, comprising a shaft 13 journaled in suitable bearings 14 and 15 on the main casting 7. Herein the worm gear 12 carries an elongated sleeve 16 extending in the direction of the bearing 15 and carrying, at its end adjacent that bearing, a driving dog ratchet 17, this sleeve with its ratchet and worm gear being normally freely rotatable on the shaft 13. Herein the sleeve 16 is adapted to be connected to the shaft 13 when desired by means of a spring pressed driving dog connection 18 (Fig. 1), which is pivotally supported at 19 on the adjacent end of a horizontal rotatable drum 20 (Fig. 2) which is secured to the shaft 65 13, the dog therefore being rotatable with the drum. As shown, the dog 18 is constantly biased into engagement with the internal teeth of ratchet 17 by a spring 21 and has a roller at its free end adapted to engage with the teeth of the inner ratchet surface of the member 17. The member 18 is also provided with a normally horizontally disposed extension 22 which protrudes beyond the drum so that through the engagement and disengagement of this extension by 70 outside mechanism, hereinafter described, the

power driven sleeve 16 may be disconnected from or connected to the drum 20.

In my improved construction, this connection or disconnection is controlled by an improved abutment member 23, hereinafter more fully described, which is, as heretofore, suitably guided at its free end in a horizontal slot in the casting 7 and pivotally connected at 24 to the vertical base of the reproducer arm 3 and adapted, as the arm is swung laterally about its usual vertical pivot 25 on the supporting frame 7, to project into the path of the dog extension 22 or be moved out of the path of the same in such manner as to cause the automatic disconnection or connection of the sleeve 16 to the drum 20. Thus, when the reproducer arm is in the full line position of Fig. 2, i. e. the position it would occupy following the reproduction of a record, and while still engaging the groove therein, the member 23 is pushed laterally out of the path of the dog 20 extension 22 by a depending extension 26 on a lower frame 27 swinging with the tone arm. The engagement of the extension 26 with the member 23 relative to the position of the reproducer arm can be varied by improved means 25 in the form of a laterally adjustable screw threaded abutment member 28 carried by said projection in position to engage the member 23, thus enabling the mechanism to be adjusted to operate with records of widely different groove 30 construction. It will be evident that with the mechanism above described when the abutment 28 engages and moves the member 23 out of the path of the dog extension 22 that the latter, under the urge of its spring 21, engages the 35 ratchet 17 and the power driven sleeve 16 is thus connected to the drum 20 to cause the latter to rotate.

As in my prior application, the drum 20 controls the movement of the reproducer mechanism, causing the reproducer to be raised from the record, swung back, and returned and lowered on the outer edge of another record during one rotation of the drum. As shown, the drum is provided with a longitudinally grooved 45 portion at the top thereof when the latter is stationary, the groove portion having opposed and spaced inclined surfaces 29 and 30 forming the bottom of the groove and likewise extended along the length of the drum. Since the drum rotates 50 in a clockwise direction, as indicated in Fig. 1, the inclined surface 29 constitutes a reproducer elevating surface while the surface 30 forms a lowering surface. As heretofore, means are also provided on the drum which co-operate with the 55 reproducer mechanism to guide and control the reproducer in its movement between these elevating and lowering positions. These means include a downwardly extending projection, or finger, 31 carried by the previously mentioned 60 swinging frame 27 which engages the elevating surface 29 upon initial rotation of the drum 20 from its stationary position shown in Fig. 1. It will be noted that this projection 31 forms a part of the member 32 which also carries the 65 depending projection 26, and that both of these projections are carried by the frame 27 which is rigidly affixed to the lower vertical end of the tone arm 3. Thus, since the latter arm is pivoted on a transverse pivot at 33 on the supporting frame structure 7, the reproducer is correspondingly lifted as the projection 31 is lifted by the elevating surface 29, this vertical movement of the reproducer being possible in addition to the swinging movement of the arm about the 70 75

bearing 25. Thus, it will be clear that as the drum 20 rotates the reproducer will be lifted from the reproduced record and will be free for lateral swinging movement. Provision is made on the drum 20 for thus moving the reproducer laterally while in this lifted position to a point out beyond the edge of the record. Herein, this is accomplished by providing on the drum 20 a guide in the form of a rib 34 (Fig. 2) which extends 5 longitudinally of the drum 20 and spirally along the outer surface thereof. At the end of the drum adjacent the bearing 15 the guide 34 extends laterally part way around the drum as indicated by the dotted lines in Fig. 2. As a result 10 of the engagement of the finger 31 with this guide, the reproducer, upon continued rotation of the drum 20, will be swung laterally toward the dotted line position thereof and of the frame 27 shown in Fig. 2. Also, as the drum continues 15 to rotate the finger 31 enters a guide passage 35 formed by the lateral portion of the rib 34 and a cam plate 36 carried by the adjacent end of the drum and projecting beyond the periphery thereof. From this passage the finger 31 upon 20 continued rotation of the drum 20 is guided into a passage 37 so disposed on the surface of the drum as to return the reproducer to a point over 25 the edge of the new record, which in the meantime has been placed on the table by record feeding mechanism hereinafter described. It will be noted that the passage 37 communicates with a lateral passage 38 on the reproducer lowering surface 30 so that as the drum 20 continues to 30 rotate the reproducer is lowered again onto the record.

It will be noted that, as heretofore, the drum 20 is so timed as to complete one revolution and have its dog extension 22 engaged by member 23 at the time or shortly after the reproducer is 40 placed on the record, the member 23 having been moved by the reproducer arm into its normal position in which it engages the extension 22 and releases the driving engagement between the dog 18 and the ratchet 17. In this connection it will 45 also be noted that a relatively light coiled spring 39, connected between a lug on the vertical portion of the tone arm and the member 23 acts not only normally to hold the member 23 in the path of the driving dog extension 22, but also 50 acts to urge the reproducer 4 gently inwardly towards the playing grooves of the new record by reason of the fact that the member 22 in this 55 position of the reproducer arm is limited in its movement by the slot in the frame 1 so as to cause the spring 39 to become slightly stressed during the outward swinging movement of the reproducer arm. It will also be noted that the 60 end of the projection 31 is provided with an anti-friction roller which materially reduces the friction between it and the guides on the drum's surface.

The location of the passage 38 relative to the record table is, as heretofore, such as to position the reproducer properly for a ten inch record. 65 Means are also provided for automatically lowering the reproducer in position to play a twelve inch record. These means include a guide passage 40, the entrance to which it will be noted is closed by guide rib 41 extending from the edge 70 of the drum and constituting one of the guide ribs of the passage 37 above described. When a twelve inch record is to be reproduced the finger 31 is diverted into the passage 40 by means which 75 will now be described in connection with the record feeding mechanism, it being noted that in

connection with the record feeding mechanism the automatic mechanism is so connected thereto as to govern the movement of the finger 31 into passages 38 or 40 according to whether a ten inch or a twelve inch record is next to be supplied by the feeding mechanism.

The record feeding mechanism, as heretofore, is driven from the shaft 13 during the time that the latter is connected through the driving dog connection on the drum with the constantly rotating sleeve 16. To this end, this shaft carries an eccentric sprocket 42 at the end thereof which is adjacent the bearing 15. This shaft also carries between said sprocket and said bearing a cam member 43, the purpose of which will presently appear. The sprocket 42 is arranged so that its pitch line is located exactly on the center of the shaft 13. This sprocket is in turn connected by a chain 44 with a larger sprocket 45 carried by the machine frame 7 on a shaft 46 20 parallel to the shaft 13 but located above the base 6. The sprocket 45 has four times as many teeth as the driving sprocket 42, and consequently will rotate through an angle of only ninety degrees during the rotation of the shaft 13 and 25 the drum 20 carried thereby through one complete revolution. Due to the eccentric positioning of the sprocket 42 relative to the shaft 13 this ninety degree rotation of the sprocket 45 will take place while the drum 20 is holding the 30 reproducer arm 3 in raised position with the projection 31 disposed in the guide passage 35. Thus, the sprocket 45 and the associated record feeding mechanism stands still during a portion of the rotation of the sprocket 42 while the latter 35 is moving in its rotation about shaft 13 toward the sprocket 45. As a result, the new record is not fed to the table until the drum actuated mechanism has moved the reproducer arm to its extreme outward position, and while the arm is 40 held stationary in this position by the movement of finger 31 along the passage 35 prior to returning the reproducer arm. An arm 47 pivoted intermediate its ends to the frame 7 carries a roller 48 at one end which engages with the cam 43 of 45 shaft 13 and carries at its other end a free sprocket 49 which engages a reach of the chain 44 between the sprockets 42 and 45, the eccentricity of cam 43 being so arranged that the slackening of the chain due to the eccentric sprocket 42 is 50 compensated for, as more fully shown and described in my copending application above referred to.

The record feeding mechanism is, as heretofore, actuated by the shaft 46. As shown 55 most clearly in Figs. 1 and 2 at the left of the table 2 a pair of horizontally disposed endless record feeding chains 50 is provided. As shown, the right hand end of each of these chains passes around a sprocket on the shaft 46 between upwardly extending shaft bearings 51 and 52 and more closely adjacent the bearing 52. It will be noted that the opposite ends of these chains 50 pass around similar idler sprockets 53 carried on a shaft 54 parallel to the shaft 46 and journaled 60 at its ends in upwardly projecting bearings 55 and 56 which like the bearings 51 and 52 project above the base 6. As indicated most clearly in Fig. 1, each link of the chain carries intermediate its length record supporting members 57 and 58. Referring more particularly to Figs. 1 65 and 2, it will be noted that each of these members 57 and 58 is provided with an arcuate slot, or opening 59 therein adapted to receive the 70 75 record feeding mechanism, it being noted that in

edge of a record and to support the record in an upright position.

It will also be noted that, as heretofore, these members 57 and 58 are alternately disposed and that the members 57 are shorter than the members 58, the members 57 constituting the holders for twelve inch records while the members 58, constitute holders for ten inch records, the curvature of the slot 59 being such as to conform to the curvature of the edge of a ten inch or twelve inch record as the case may be. The members 57 and 58 which are disposed on the upper reaches of the chains 50 are adapted to receive records inserted from the top in the slots therein. It will be noted that upon rotation of the shaft 46 these members 57 and 58 will feed their records to the right and toward the record playing table 2, each record as it approaches the table being moved about the shaft 46 as an axis into an inclined position above the table and gradually lowered toward a horizontal position above the table in which position the center hole in the record is disposed substantially over a record centering pin on the table 2.

Referring particularly to Fig. 10 it will be noted that, herein, this pin is formed with an eccentric annular and tapered upper end portion which terminates in an eccentric apex 60. The engagement of the central aperture of the record with the rotating eccentric end of the pin causes the record to be moved laterally to the right and away from the downwardly traveling record holder a sufficient distance to disengage the edge of the record from the groove 59 in the holder and to settle the record into properly centered position on the table. More particularly it will be noted that as the record is lowered onto the pin, the center aperture therein is engaged by the eccentric annular end of the rotating pin which in effect cams the record laterally out of the groove of the record holder, thus permitting the record to settle by its own weight into position on the concentric portion 60a of the pin located below the eccentric portion thereof in which position it is centered relative to the table.

A suitable aperture 61 is provided in the base 6 beneath the magazine through which the record holders pass downwardly beneath the mechanism and again come up at the left (Fig. 2) in position again to receive another record. As herein shown, the conveyor is arranged to hold six ten-inch and six twelve-inch records which may be automatically reproduced, or either ten inch or twelve inch records may be inserted and played in the order in which they are inserted in the magazine.

Associated with the record feeding mechanism, as heretofore, is reproducer controlling mechanism for causing the reproducing mechanism to lower the reproducer in the correct position to play whichever size of record is being fed to the table. This controlling mechanism includes a cam 62 affixed to the shaft 46, and herein shown as an integral part of the sprocket 45. This cam is provided with two enlargements 63 (Fig. 1) disposed diametrically opposite one another, having opposite portions of uniform diameter 64 therebetween. Co-operating with this cam is a roller 65 engaging the surface 64 and adapted when actuated by an enlargement 63 to move a reciprocable frame 66 which is supported upon the main frame 7 directly beneath the base 6 but above the swinging frame 27 of the reproducer mechanism. This frame 66 has a right-hand end projection 67 which is movable into and out of a

position in which it is disposed in the path of movement of an upstanding projection 68 of member 32 of the reproducer mechanism when the latter is being returned into a position over the record by the projection 31 as it leaves the passage 35 and enters the passage 37 above described.

Considering more particularly the operation of this reproducer controlling mechanism, it will be noted that, as shown in Fig. 1, the record which has just been reproduced is a ten-inch record delivered by a holder 58 while the next record in the machine, assuming that the next record holder 57 contains a record, will be a twelve-inch record. When the drum 20 starts to rotate, as a result of the abutment 28 engaging and displacing the member 23 from the dog extension 22, the depending projection 31, acted upon by the elevating surface 29, will cause the reproducer arm 3 to be raised and swung laterally through engagement with the guide rib 34 into the guide passage 35 wherein it is beyond the edge of a twelve-inch record on the table. However, before the connected arm 27 of the reproducer arm can swing back sufficiently toward the center of the table 25 to enable its projection 31 to enter the guide passage 38, and while the depending projection 31 is directly opposite the entrance to the guide passage 40, one of the projections 63 on the cam 62 engages the roller 65 of the carriage 66 and, moving the latter against the action of its spring, causes the projection 67 on the carriage to be moved into the path of the upstanding projection 68 of member 32, thus preventing further inward movement of the finger 31. As the drum continues to rotate, the member 31 will be forced over the guide rib 41 into the guide passage 40 and the reproducer 4 will be lowered onto the edge of a twelve-inch record as the projection 31 moves down the slope 30 of the drum's surface. The projection 68 will thereby be automatically lowered from the projection 67, by the lowering of the reproducer, and the reproducer will then be urged under the action of spring 39 into the first playing groove of the record, while the drum 20 will be stopped in the position shown in Fig. 2 as before described.

The next record deposited by the feeding mechanism, if all the record holders are filled, will be a ten-inch record. In this case, however, the depending projection 31 will be free to complete its movement along the passage 37 and into the passage 38, since the roller 65 will be in engagement with a dwell portion 64 of the cam 62 and projection 67 will not be moved into the path of the inwardly swinging projection 68.

During this return movement of the reproducer arm relative to the table and just before a new record is disposed on the table, the reproduced record is discharged from the table. This is accomplished herein by the projection of a crank arm 69 formed on that end of shaft 13 which is remote from the drum 20. This arm is adapted to be rotated with the shaft from its inoperative position shown in Fig. 1 in which it is located below the base 6 into an elevated position in which it projects upwardly through a slot 70 in said base. This arm is provided at its free end with a roller 71 which is adapted to engage the over-hanging edge of any record on the table and to elevate 70 the record sufficiently to raise the central aperture of the record above the apex 60 of the centering pin whereupon, and due to the rotation of the table, the record is discharged to the right as viewed in Figs. 1 and 2. By reason of the con-

tinued contact of the lower edge of the tilted record with the rotating table, the record is caused to engage the side wall 72 as it slides from the table into a record compartment 73 in which the discharged record assumes an inclined position parallel to the left hand record supporting wall 74. It will be noted that the bottom and side walls of compartment 73 are suitably lined with felt or other suitable material 75 for cushioning the descent of the records into the compartment. Due to the direct connection of the arm 69 to the drum driving shaft 13, said arm, subsequent to the discharge of the reproduced record, and while the new record is moving downwardly toward the table, swings around into a position below the base 6 before the new record is placed on the table.

Means are also provided by which the playing of the record on the table can be immediately discontinued, the record discharged into the discharged-record compartment, and the next record in the magazine fed to the table. This is accomplished by a manually reciprocable rod 74a projecting from the front of the cabinet which is connected to a generally vertical tripping lever 75a pivotally supported on the frame 7 behind the reproducer tripping member 23 and in position to engage and trip the same upon manual operation of the rod 74a.

30 The mechanism above described, save as regards certain features above brought out, is substantially that disclosed and claimed in my co-pending application, previously referred to, in which the record feeding and reproducer controlling mechanism is more fully described.

In accordance with the present invention improved means are provided in connection with the record holding conveyor, or magazine, by which the operation of the phonograph is automatically controlled. Referring particularly to Figs. 1, 2, and 3, it will be noted that a shaft 76 is located alongside the record holding magazine normal to the shaft 46 and is rotatably supported between upstanding bearing members 77 and 78 carried by the upper face of the base 6. It will be further noted that the shaft 76 occupies a position close to the base 6 and extends beneath and closely adjacent the record feeding shaft 46. Carried by the shaft 76 and upstanding therefore, is a record engaging frame, or hoop, the outline of which is shown most clearly in Fig. 1. This frame includes the opposite upstanding end portions 79 and 80 which extend through and are permanently fixed in the shaft 76 and a middle connecting portion 81 which, with a ten-inch record in the magazine, or as shown in Fig. 2 when the last record has been fed and the magazine is empty, is located directly above and parallel with the shaft 76. The end member 79 is further extended diametrically through the shaft 76 to provide a depending switch actuating arm 82 which extends through a slot in the base 6 and depends therebelow. The depending arm 82 is, accordingly, pivotally connected intermediate its ends by a pin and slot connection with the switch actuating rod 83 of an electric switch 84 suitably supported beneath the base 6. As indicated most clearly in Fig. 9, the switch 84 has its leads 85 connected in series with the leads 86 of motor 1 in the power circuit 87 for said motor; and that the switch 84 has a movable contact member 88 adapted to co-operate with relatively long, resilient, stationary contact members 89, thus to permit a considerably lateral move-

ment of the switch rod 83 while maintaining said co-operating contact members in engagement.

A retractile spring 90 extended between the switch casing and the lower extended end of said arm 82 serves constantly to bias said shaft 76 for rotation in a counter clockwise direction, as viewed in Fig. 3, and to bias the hoop supported thereby in a direction toward the record carrying magazine and into the left hand dotted or "off" position shown in Fig. 3, in which position 10 the co-operating stationary and movable contact members of the switch 84 are open or disconnected as indicated in the right hand dotted position in Fig. 9.

As will be evident from Fig. 3, when a record 15 is placed in any record holder 57 or 58 of the magazine the portion 81 of the hoop will be engaged by the periphery of the record and will be rotated about the shaft 76 in a direction away from the magazine into one of the "on" positions 20 indicated in Fig. 3. Thus, the insertion of a ten-inch record in the magazine will move the hoop into the center full line position of Fig. 3, while the insertion of a twelve-inch record will still further rotate the hoop into the right hand dotted 25 "on" position of this figure. As will be evident from Fig. 9, when the hoop is in the extreme left-hand position of Fig. 3, switch 84 is open, whereas in the position which the hoop assumes when a ten-inch or a twelve-inch record is occupying the magazine, switch 84 is closed.

It will thus be evident that to start the phonograph in operation all that is necessary is to place one or more records to be reproduced in the magazine and that the first record placed in the 35 magazine will actuate the control switch 84 to close the motor circuit and set the machine in operation.

Means are provided, however, to delay the movement of the frame to its switch "off" position 40 while the last record in the magazine is being reproduced on the table. To this end a notched disk 92 is fixed to the shaft 46 adjacent the frame supporting shaft 76. As shown most clearly in Fig. 1, the disk 92 is provided with 45 four notches 93 which are thus always in timed relation with the record feeding mechanism and which are adapted to be entered by a laterally extended pin 94 (Fig. 3) carried by the shaft 76 whenever the shaft 46 is rotated into a position 50 to bring a notch 93 in disk 92 opposite the pin 94, thus permitting the frame to move to the dotted or "off" position indicated in Fig. 3.

When the last record is being delivered from the magazine, it rides along the downwardly curved, forwardly projecting portion 95 of the frame portion 81, thus holding the switch 84 in its "on" position until the notch 93, which is opposite the pin 94, has passed beyond said pin. The pin then engages the unnotched portion of 60 the disk 92 and remains in this position while the record is being placed on the table and while it is being reproduced. When the reproducer has traversed the last record and has reached the position indicated in Fig. 2 in which it releases the driving dog extension 22, the drum 20 will begin another revolution, swinging the reproducer mechanism outwardly beyond the table and discharging the reproduced record as previously described. These operations will be performed prior to the operation of the record feeding mechanism due to the delayed operation of the latter by reason of the eccentric sprocket wheel 42. Upon actuation of the record feeding mechanism, however, the notched disk 92 will be 70 75

advanced until the pin 94, under the urge of spring 90, drops into a notch 93 thereof, thus causing the switch 84 to open and shut down the machine. It will be noted that when the magazine is empty, the mechanism is thus enabled to complete the reproduction of the last record supplied to the table and discharge the record before the automatic stopping of the machine takes place.

10 In connection with Fig. 9, it will also be noted that a manually operable switch 96 is provided which, like the switch 84, is connected in series in the power circuit for the motor 1. This switch is supported on an end wall of the cabinet beneath the discharged record compartment and is actuated by a vertical operating rod 97 which extends upwardly through the base plate 6 and between the cabinet and the end wall 98 of said record compartment. A knob 99 is provided at the free end of rod 97 above the base plate 6 by which the rod is adapted to be moved downwardly to open the switch or upwardly to close it. It will be noted that the switch 96 is adapted to remain in either the open or the closed position thereof until it is operated. The provision of this master switch permits an operator to shut down the machine at any time without waiting for the records in the magazine to be reproduced, this switch of course disabling the automatic stopping and starting of the machine by the records in the magazine.

Improved means are also provided for automatically opening the master switch whenever, carelessly or otherwise, the discharged record compartment becomes full of records. Referring particularly to Fig. 8, it will be noted that the end wall 98 of said compartment has a transverse slot 100 adjacent the bottom thereof which is normally closed by a resilient member 101 secured to the outside face thereof and consequently capable of flexing outwardly when engaged by the bottom edge of an inclined record which is being discharged into said compartment. The records first discharged into the compartment rest in an inclined position on the bottom and side walls thereof, but, as indicated in Fig. 8, when the compartment is nearing its capacity, the bottom edges of the records engage the end wall 98 of the compartment below the slot 100 therein, each record engaging said wall at a point nearer said slot than the preceding record, until finally the record designated in Fig. 8 by numeral 102 strikes the resilient member 101 and flexing the same outwardly engages a lateral projection 103 on rod 97, causing said rod to be suddenly depressed into its switch open position. Provision of the above described automatic operation of the master switch 96, of course, prevents the continued operation of the phonograph without removing the discharged records from the compartment. Preferably said compartment is adapted to hold at least twelve records, which comprise a full magazine. It will be noted that when the master switch has thus automatically been opened by a full record compartment, it is not possible to operate the machine in any reasonable manner until these records have been removed from the compartment.

In connection with the reproducer tripping mechanism herein described as actuated by the inward movement of the depending projection 26, it will be noted that improved provision is made for tripping said reproducer mechanism upon the inward movement of the frame member 27 of said mechanism. This mechanism is es-

pecially adapted to trip the reproducer mechanism when records having an inner eccentric needle groove are used in the machine, it being noted that, as before, the tripping action takes place upon the inward movement of the reproducer arm.

Considering this mechanism more specifically, it will be noted that the swinging frame member 27 of the reproducer mechanism has an arm 104 (Fig. 1) rigidly affixed thereto and depending therebelow in a position to overlie an arcuate rack member 105 which is carried by member 23 and extends rearwardly therefrom in the general direction occupied by the tone arm during reproduction of a record, it being noted that this rack member conforms to an arc struck about the pivotal bearing 25 of the tone arm. As shown most clearly in Figs. 4 through 6, the arm 104 is provided with integral depending ears 106 between which a horizontally extended gravity pawl 107 is pivotally supported for a limited vertical movement. It will also be noted that the pawl 107 is provided with a bottom rack engaging tooth 108 which is adapted to engage the ratchet teeth 109 on the upper face of the ratchet member 105. This pawl 107 is bifurcated at its free end and has a tooth shielding member 110 pivotally supported between said bifurcations. This shielding member 110, as shown most clearly in Fig. 4, has a normally vertically disposed eccentric slot 111 therein through which the pivot pin 112 of pawl 107 extends. Due to the eccentric location of said slot the shielding member 110 normally occupies, by gravity, the position shown in Fig. 4 in which the tooth shielding lug 113 thereof is located beneath the tooth 108 of said pawl, thus preventing engagement of said tooth with the rack.

During the reproduction of a record, the frame member 27 of the reproducer mechanism with its pawl 107, is located remote from the rack 105 and approaches said rack only when reproduction of the record is nearing completion. As the pawl 107 approaches the rack, the tooth 108 thereof is shielded by the lug 113 so that during the continued inward movement of the reproducer arm the tooth 108 is prevented from engaging the rack member and actuating the arm 23 to release the dog extension 22. Consequently the pawl 107 overrides the rack 105, as illustrated in Fig. 4. If, however, a record having an inner eccentric needle groove, as the groove 113a of the double faced record shown in Fig. 3, has been reproduced, when the reproducer needle enters the eccentric groove the arm 27 will be given an oscillatory movement, as will be readily understood. Upon the first reverse movement of the reproducer arm 27 in which the pawl 107 is moved in a direction away from rack 105, the tooth shielding member 110 will fulcrum about the lug 113 thereof (Fig. 6) thus bringing the tooth 108 into engagement with the rack teeth 109. On the return movement of the reproducer arm under the action of the eccentric groove 113a, the rack 105 will be displaced laterally by the pawl 107 in a direction to release the dog extension 22. If the first oscillation of the reproducer mechanism does not move member 23 sufficiently to effect such disengagement of the dog extension, it will be noted that each succeeding oscillation of the reproducer arm will advance the rack member 105, thus ultimately causing the tripping of the reproducer mechanism.

Due to the fact that the spring 39 is constantly urging the member 23 into dog engaging position

- against the notching action of the pawl 107, means are provided to latch the member 23 after each actuation thereof by pawl 107 against return movement under the action of the spring 39.
- 5 To this end the free, or abutment, end of the member 23 is provided with longitudinal steps 114 (Fig. 7) on the bottom dog engaging surface thereof. As will be evident, each time that the reproducer arm advances the member 23 laterally, the dog extension 22 will engage a new latch face on the stepped portion of said member, thus permitting the same to be moved in a progressive manner, by repeated actuation of pawl 107, out of engagement with the dog extension 22.

9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

magazine, the insertion of a record actuating the frame by its engagement with the portion 81 thereof to close the motor switch 84. The machine will then continue its cycle of operation where it was interrupted by the entrance of pin 5 94 into the notched disk 92.

Here it should be stated that under these conditions the clutch dog 18 is in drum driving engagement with the ratchet 17, although the reproducer arm is outside the table. This is made possible by reason of the fact that when the reproducer arm drops to its present abnormally low position below the table, the dog holding member 23, which it will be noted is pivoted to the vertical portion of the tone arm a considerable distance below the lateral pivot pin 33 thereof, is withdrawn longitudinally, when the tone arm assumes this extreme lowered position, out of its normal position in which it engages the dog extension 22. Consequently, the drum 20 will continue to rotate through successive cycles until the record which has been inserted in the magazine is supplied to the table, it being noted that the reproducer arm 3 is raised and lowered during each of these successive cycles due to the engagement of the finger 31 with the cam faces 29 and 30 of the drum so that if a record is supplied to the table, the reproducer will be properly deposited on the edge thereof. If the new record which initiates the automatic operation of the machine is placed in the record holder of the magazine nearest the table, the drum 20 will make only one complete revolution. If the new record, however, is inserted farther back in the magazine, several rotations of the drum may be necessary to advance the record to the table, all of which, however, will be automatically performed.

As regards the general construction above described, attention is directed to the fact that the present invention provides a phonograph which is extremely simple in its operation and is completely automatic. It will be understood that, although a manually operable master control switch is provided, in the operation of the phonograph this switch will normally remain in its closed position and will not interfere with the completely automatic operation of the phonograph under control of the record actuated switch 84 above described, unless the machine is improperly operated. As a result of the novel means for automatically moving this master switch into its contact open position by discharging a record into a full discharged-record compartment, the automatic operation of the machine is automatically stopped before damage is done either to the machine or the records. Thus a careless or immature person, or one entirely unfamiliar with the operation of the machine, cannot, by operating it, cause damage thereto. The master switch also provides means for stopping the automatic operation of the machine when there are records in the magazine and it is not desired to continue playing the records, the phonograph being instantly stopped by the opening of this switch.

As a result of my improved automatic control of the phonograph, by the records inserted in the magazine, it is possible to play single records or a series of records, irrespective of their diameter, simply by placing them in the magazine in the desired order. Furthermore, it is possible to examine the records in the magazine and change any record therein during the operation of the machine, thus providing a very

flexible arrangement. If it is desired to reproduce a series of records having the same diameter, as a series of ten-inch records on a series of twelve-inch records, the insertion of the first 5 record, regardless of its size, will automatically start the phonograph in operation. Likewise a mixture of ten-inch and twelve-inch records can be inserted in the magazine and automatically reproduced in the order of their position in the 10 magazine. This control mechanism, which is governed by the presence in the magazine of a record of any size, also, by reason of the delayed control means associated with the record feeding mechanism, permits the last record fed from the 15 magazine to be reproduced before stopping the operation of the phonograph.

By reason of the improved pin for centering the records on the rotating table, by which the central aperture of the record first engages a 20 tapered eccentric end portion of the pin, greatly improved operation of the machine results, since an increased lateral movement of the record is made possible as it engages the eccentric portion of the rotating pin. This increased lateral 25 movement of the record, by which it is laterally extracted from the groove of the record holder, permits the record magazine to be located a little farther away from the table and permits the machine to operate satisfactorily with records having a considerable variation in diameter 30 due to this increased lateral movement of the record under the camming action of the eccentric pin.

In connection with the improved mechanism 35 for tripping the reproducer mechanism, it will be noted that the phonograph of the present invention is adapted not only to play, without adjustment, records of different diameter, either singly or mixed together in the magazine, but 40 also that it is adapted to reproduce records having either spiral or eccentric inner needle grooves, without any change in the mechanism. By reason of the improved gravity pawl construction the eccentric groove tripping means is inoperative 45 when records having spiral grooves are in use, the tripping pawl being permitted to move freely over the ratchet teeth of the tripping member without engaging with them. It should also be noted that the improved pawl and ratchet 50 construction provided for tripping the reproducer mechanism with eccentric groove records is operative irrespective of the degree of eccentricity of the groove on the record since the mechanism provided accomplishes the tripping 55 in a progressive manner, step by step, as the reproducer traverses the groove through successive rotations of the record.

Here attention is also directed to the advantages resulting from the laterally adjustable 60 abutment means carried by the swinging frame of the tone arm by means of which the tripping engagement of the reproducer mechanism with the dog clutch latching member can be varied in setting up the machine to meet the 65 requirements of a greater number of conditions and variations in construction encountered in the records of different manufacturers, thus greatly extending the scope of the machine.

70 While I have in this application specifically described one embodiment which my invention may assume in practice, it will be understood that the same is shown herein for illustrative purposes only, and that the invention is not limited thereto but may be modified and embodied

in various other forms without departing from its spirit or the scope of the appended claims.

What I claim as new and desire to secure by Letters Patent is:

1. In a phonograph, mechanism for automatically reproducing records including record receiving means disposed when in the same vertical operative position to receive and support simultaneously a plurality of records of different diameters inserted therein, and means controlling 5 said mechanism for effecting automatic reproduction of a single record deposited on said record receiving means and irrespective of the diameter of said record setting said mechanism in operation to reproduce said record by the deposit 10 of said record on said record receiving means.

2. In a phonograph, mechanism for automatically reproducing a record including record receiving means disposed to receive a record in upstanding position thereon, and means operative by the record controlling said mechanism for effecting automatic reproduction of the record and setting said mechanism in operation upon the deposit of said record on said record 20 receiving means.

3. In a phonograph, mechanism for automatically reproducing a series of records including record receiving means disposed when in the same position to receive therein vertically disposed records of different diameter, and means controlling said mechanism effecting automatic reproduction of said records successively and setting said mechanism in operation upon the deposit of the first record of the series in said 30 record receiving means.

4. In a phonograph, mechanism for automatically reproducing records including record receiving means disposed when in the same operative position to receive and support simultaneously records of different diameters, and means 40 controlling said mechanism for effecting automatic reproduction of a record on said record receiving means and setting said mechanism in operation by the deposit of but a single record on said record receiving means, said record receiving means being adapted to permit the removal of any record therein or the insertion of additional records while continuing the automatic 45 operation of the phonograph.

5. In a phonograph, mechanism for automatically reproducing a series of records including a record receiving magazine having means disposed to receive one or more vertically disposed and laterally spaced records therein, and means for setting said mechanism in operation automatically by the insertion in said magazine of the first record of a series to effect the automatic 55 reproduction of all the records of the series.

6. In a phonograph, mechanism for automatically reproducing a series of records having a magazine having means disposed to receive the records in vertical laterally spaced relationship, and mechanism for initiating the automatic reproduction of the series upon the insertion of the first record of the series in the magazine and continuing the automatic operation of said reproducing mechanism so long as a record remains in said phonograph.

7. In a phonograph, mechanism for automatically reproducing a series of records having a magazine adapted to receive the records in vertically laterally spaced relationship, and mechanism for initiating the automatic reproduction of the series upon the insertion of the first rec- 75

ord of the series in the magazine, and continuing the automatic operation of said reproducing mechanism so long as a record remains in said phonograph, said magazine comprising spaced 5 upstanding record supporting members and permitting the insertion and withdrawal of the records in the magazine during the automatic reproducing operation of the phonograph.

8. In a phonograph, mechanism for automatically reproducing a series of records including a record rotating table, reproducer mechanism for reproducing a record on said table, a record receiving magazine adjacent said table having means for adapting it to support simultaneously 10 a series of records of the same or different diameter, record advancing mechanism for feeding records from said magazine to said table, and means responsive to the insertion of the first record of a series in said magazine for initiating 15 the automatic operation of said mechanism to reproduce successively the records in said magazine.

9. In a phonograph, a record rotating table, a record receiving magazine, co-operating record 20 feeding, reproducing and discharging mechanisms, means governed by the first record inserted in said magazine for initiating automatic operation of said mechanisms, and means governed by the last record remaining therein for controlling 25 said mechanisms to effect automatic feeding and reproduction of all of said records inserted in said magazine.

10. In a phonograph, a record rotating table, a record receiving magazine, cooperating record 30 feeding and reproducing mechanisms, means for discharging a reproduced record from said table, and mechanism governed by the first record inserted in said magazine and by the last record remaining therein for controlling said mechanisms 35 to effect automatic feeding and reproduction of all of said records and having means for starting said mechanisms upon the insertion of the first record in said magazine and means for stopping said mechanisms after the last record has been 40 fed from said magazine and reproduced on said table.

11. In a phonograph, a record rotating table, a record receiving magazine, cooperating record feeding, reproducing and discharging mechanisms, and mechanism governed by the first record 45 inserted in said magazine and by the last record remaining therein for controlling said mechanisms to effect automatic feeding, reproduction, and discharge of all of said records and having means for starting said mechanisms upon the insertion of the first record in said magazine, and means for stopping said mechanisms after the last record has been fed from said magazine and discharged from said table.

12. In a phonograph, mechanism for automatically reproducing a series of records including a record receiving magazine having a plurality of spaced upstanding record receiving members each adapted to support a record independently of adjacent records, mechanism for initiating the automatic operation of said mechanism upon the insertion of the first record in said magazine, and means for continuing said automatic operation until the last record in the magazine has been 70 reproduced.

13. In a phonograph, a record rotating table, a record receiving magazine having means for supporting one or more records, each independently of the other, mechanism for reproducing 75 the records in said magazine, and controlling

mechanism for said reproducing mechanism operative to effect the automatic reproduction of all records in the magazine on said table and including an automatically operated starting and stopping mechanism which is controlled by the 5 insertion and the removal of the first and last records of the series placed in said magazine.

14. In a phonograph, mechanism for automatically reproducing a series of records including a record receiving magazine, a record rotating 10 table, and means controlling said mechanism to effect automatic reproduction on said table of all records in said magazine and the discharge of the reproduced record therefrom including a control member displaced by the insertion of the first 15 record therein to indicate automatic reproduction and maintained in displaced position by the records in said magazine.

15. In a phonograph, mechanism for automatically reproducing records including a record holding magazine adapted to receive and support one or more records therein in upright position, and means for automatically setting said mechanism in operation including a control member disposed 20 normal to the records in said magazine and in position to be engaged and operated by the first record inserted in said magazine, to initiate automatic reproduction of the latter.

16. In a phonograph, mechanism for automatically reproducing records including a record holding magazine having a plurality of record holders adapted to receive and separately support a plurality of records in upright position, and means for controlling the automatic operation of said mechanism including a control member extended along one side of said magazine and normal to the record holders thereof in position to be engaged and operated by a record inserted in any of said record holders to start the automatic operation of said reproducing mechanism. 40

17. In a phonograph, mechanism for automatically reproducing records including a record holding magazine adapted to receive and support a plurality of records of different diameter in upright position therein, and means for controlling the automatic operation of said mechanism including a control member extended alongside said magazine in position to be engaged and operated to start said mechanism by the first record inserted in said magazine regardless of the 50 diameter thereof.

18. In a phonograph, mechanism for automatically reproducing a series of records including a record receiving magazine, means for setting said mechanism in operation to effect the automatic reproduction of all the records in the magazine including a control member located in position to be engaged and operated by any record placed in said magazine and to be maintained in operative position until all the records in said 60 magazine have been reproduced.

19. In a phonograph, mechanism for automatically reproducing a series of records including a record receiving magazine, means for setting said mechanism in operation to effect the automatic reproduction of the records in the magazine including a control member located in position to be engaged and operated by any record placed in said magazine and to be maintained in operative position so long as a record remains in said magazine, and means for maintaining said control member in the aforesaid operative position after the last record has been fed from the magazine and while it is being reproduced.

20. In a phonograph, mechanism for automati- 75

- cally reproducing a series of records including a record receiving magazine, means controlling said mechanism to effect automatic reproduction of a series of records of mixed diameters in said magazine including a control member engaged and actuated by the first record inserted therein to indicate said automatic reproduction irrespective of their diameter and maintained in actuated position so long as any record is in said magazine, and means for continuing to effect automatic reproduction after the last record irrespective of its diameter has left the magazine and until said record has been reproduced.
21. In a phonograph, mechanism for automatically reproducing a series of records including a record rotating table, reproducer mechanism, a record receiving magazine having a plurality of record holders supporting records in substantially upright position, record advancing mechanism for feeding records in said magazine to the table, and a control member disposed alongside said record holders in position to be engaged by the edge of a record inserted in any of said holders and controlling the operation of said automatic reproducing mechanism.
22. In a phonograph, mechanism for automatically reproducing a series of records including a record rotating table, reproducer mechanism for reproducing a record on said table, a record receiving magazine having a plurality of record holders each adapted to receive a record, means for advancing said record holders toward said table, and means including a control member located alongside said record holders and in position to be engaged by the records in said holders for controlling the automatic operation of said mechanism, said control member being displaced by the insertion of a record in any of said holders and held displaced by records therein whereby to continue the automatic operation of said mechanism so long as a record remains in said magazine.
23. In a phonograph, mechanism for automatically reproducing a series of records including a record rotating table, reproducer mechanism for reproducing a record on said table, a record receiving magazine having a plurality of record holders each adapted to receive a record, means for advancing said record holders toward said table, and means including a control member located alongside said record holders and in position to be engaged by the records in said holders for controlling the automatic operation of said mechanism, said control member being displaced by the insertion of a record in any of said holders whereby to continue the automatic operation of said mechanism so long as a record remains in said magazine, and means governing the return of said control member to its normal position upon feeding of the last record in said magazine to the table and disabling said automatic mechanism upon reproduction of the last record.
24. In a phonograph, a record rotating table, a reproducer, mechanism for automatically supplying a record to said table for reproduction and discharging the same from the table including a record receiving magazine, means for setting said mechanism in operation to reproduce a record inserted in said magazine including a control member adapted to be engaged by the inserted record and moved to an operated position thereby, and means for delaying the return movement of said member until said record has been reproduced.
25. In a phonograph, a record rotating table,
- a reproducer, mechanism for automatically supplying a series of records to said table for reproduction including a record receiving magazine having means disposed to receive a plurality of records in different positions therein, means for setting said mechanism in operation to reproduce the records inserted in any position in said magazine and automatically set in operation by the insertion of any record therein including a control member engaged by any inserted record and moved to an operated position thereby, and means for delaying the return movement of said member until all records have been reproduced.
26. In a phonograph, mechanism for automatically reproducing records including a record rotating table and a record holding conveyor having a plurality of laterally spaced parallel record holders each adapted to support a record therein, means for operating said conveyor to feed said records successively to said table to be reproduced, means for controlling the automatic operation of said mechanism including a movable control member located adjacent said magazine and normal to said record holders in position to be engaged and moved by a record inserted in any of said holders from a normal mechanism inoperative position into a mechanism operative position to start the automatic operation of said reproducing mechanism, and means for delaying the return movement of said control member to mechanism inoperative position after the last record in said magazine has been fed to said table and until said record has been reproduced.
27. In a phonograph, mechanism for automatically reproducing records including a record rotating table and a record holding conveyor having a plurality of laterally spaced parallel record holders each adapted to support a record therein, means for operating said conveyor to feed said records successively to said table to be reproduced, means for controlling the automatic operation of said mechanism including a movable control member located adjacent said magazine and normal to said record holders in position to be engaged and moved by a record inserted in any of said holders from a normal mechanism inoperative position into a mechanism operative position to start the automatic operation of said reproducing mechanism, and means for delaying the return movement of said control member to mechanism inoperative position after the last record in said magazine has been fed to said table and until said record has been reproduced, said means comprising a notched member movable with said record feeding mechanism and a co-operating member carried by and movable with said control member and engaging an unnotched position of said notched member during feeding and reproducing of said last record and adapted to enter said notches and permit said control member to move to inoperative position only after said last record has been reproduced.
28. In a phonograph, mechanism for automatically reproducing records including a longitudinally movable record holding conveyor adapted to receive and separately support a plurality of transversely disposed records in upright position thereon, means for controlling the automatic operation of said mechanism including a control member located alongside said conveyor and movable toward and away from said conveyor to control the stopping and starting of said mechanism, and means normally biasing said control member toward said conveyor, said control member being moved away from said conveyor by a

record placed thereon and being held in displaced position by said record as the latter is moved therealong by said conveyor.

29. In a phonograph, mechanism for automatically reproducing a series of records including a record rotating table, a record holding conveyor adapted to support a plurality of transversely disposed upstanding records and movable toward said table to feed records thereto, and means 5 controlling the automatic operation of said mechanism including a relatively stationary control member located alongside said conveyor and having a limited movement toward and away from said conveyor, means constantly biasing said member toward said conveyor in which position said mechanism is stopped, and means to set said mechanism in operation in response to the movement of said control member away from said conveyor by the insertion of a record on said conveyor.

30. In a phonograph, mechanism for automatically reproducing records including a record rotating table, and a longitudinally movable record holding conveyor adapted to receive a plurality of records in upright position and feed them to and deposit them in horizontal position on said table, means for controlling the automatic operation of said mechanism including a pivoted shaft extended lengthwise of said conveyor, a frame carried by said shaft having a portion extending alongside and above said conveyor in position to be engaged and laterally displaced by a record placed thereon, and means normally biasing said frame toward a mechanism 30 stopped position.

31. In a phonograph, mechanism for automatically reproducing records including a record rotating table, a record-holding belt conveyor adapted to receive a plurality of transversely disposed upright records thereon, said records being moved by said conveyor from an upright position on said conveyor to a horizontal position on said table, and means for controlling the automatic operation of said mechanism including a control member extended alongside said conveyor in position to be engaged by the moving records thereon and having a downwardly curved portion adjacent said table along which said records move in their inclined position as they 40 approach the table.

32. In a phonograph, mechanism for automatically reproducing records including a record rotating table and a record receiving magazine, means for feeding records from said magazine 55 to said table, and means for controlling the automatic operation of said mechanism including a control member located adjacent the magazine and movable laterally away therefrom upon the insertion of a record in said magazine, means 60 constantly biasing said control member into a mechanism stopped position adjacent the magazine, and means for delaying the return movement of said control member until after the last record in said magazine has been fed to the table 65 and reproduced thereon, said means including co-operating interlocking members carried by said record feeding mechanism and said control member.

33. In a phonograph, mechanism for automatically reproducing records including a record rotating table and a record receiving magazine adapted to receive records in a transverse and upright position thereon, and means for feeding records from said magazine to said table and 70 reproducing the same thereon, means for con-

trolling the operation of said mechanism by the insertion of a record in said magazine including a control member pivotally supported for lateral movement from a normal mechanism stopping position in which it is adjacent said magazine to a displaced mechanism starting position, and means for delaying the return of said control member to mechanism stopping position until after the last record on said magazine has been fed to said table and reproduced thereon including co-operating interlocking members, one of which is carried by said record feeding means and the other of which is carried by said control member.

34. In a phonograph, mechanism for automatically reproducing a series of records including a record receiving magazine and cooperating record feeding and reproducing means, means for effecting the automatic reproduction of all the records in the magazine including a control 15 member located in position to be engaged and operated by any record in the magazine and to be maintained in operative position until after the last record has been fed from the magazine and reproduced, said means including a notched 20 disk associated with said mechanism and a co-operating member associated with said control member and adapted to enter a notch in said disk to permit said control member to move into inoperative position, said mechanism being so 25 timed that said co-operating member engages an un-notched portion of said disk during the feeding and reproducing of said last record.

35. In a phonograph, mechanism for automatically reproducing records including a record rotating table, a record receiving magazine, and record feeding means for transferring records from said magazine to said table, means for setting said mechanism in operation to effect the automatic reproduction of the records in the 35 magazine including a control member located in position to be displaced from a mechanism stopped position to a mechanism operative position by any record placed in said magazine and adapted to be maintained in operative position 40 so long as the record remains in said magazine, means biasing said member toward its mechanism stopped position, and means for maintaining said control member in the aforesaid operative position of said mechanism while said record is being fed to the table and reproduced 45 thereon including a disk rotatable by said mechanism and having spaced peripheral notches therein and a co-operating interlocking member carried by said control member and adapted to 50 engage an un-notched portion of said disk during the aforesaid record feeding and reproducing operations.

36. In a phonograph, mechanism for automatically reproducing a series of records including a record rotating means and means for discharging reproduced records therefrom, a magazine adapted to receive the discharged records in substantially upstanding position therein, and means governed by an upstanding record in said magazine and operative only when the latter is filled 60 for controlling said reproducing mechanism.

37. In a phonograph, mechanism for automatically reproducing a series of records including a record rotating means and means for discharging reproduced records therefrom, a magazine adapted to receive the reproduced records, and means operative when a predetermined number of records has accumulated in said magazine and stationary until the last record of the predeter- 70 75

mined number is received in the latter, controlling said reproducing mechanism.

38. In a phonograph, mechanism for reproducing a series of records including a record rotating table and means for discharging reproduced records therefrom, a magazine adapted to receive the reproduced records, and means engaged and operated by the last record automatically operative to stop the reproduction of records upon the accumulation of a predetermined number of records in said magazine.

39. In a phonograph, a record rotating table, a magazine adapted to receive records to be reproduced in substantially upstanding position therein, a second magazine adapted to receive the reproduced records from the table in substantially upstanding position in said magazine, automatic mechanism for reproducing a series of records including mechanism for supplying said substantially upstanding records from said first magazine to the table and for discharging the same when reproduced into substantially upstanding position in said second magazine, and controlling mechanism having means automatically operative to stop said record reproducing mechanism when a predetermined number of records have accumulated in said second magazine.

40. In a phonograph, means for automatically reproducing a series of records including a record rotating table and means for discharging reproduced records therefrom, a magazine adapted to receive the reproduced records, and control means responsive to a full magazine and having a control member engaged and actuated by the last record receivable in said magazine for automatically stopping said reproducing mechanism when said magazine is full.

41. In a phonograph, means for automatically reproducing a series of records including a record rotating table, a magazine adapted to receive the reproduced records, and controlling means responsive to a full magazine and having a controlling member engaged and actuated by the last record for automatically stopping said reproducing mechanism, and a manually operable control member operable from the exterior of said magazine for actuating said controlling means and member to stop said reproducing mechanism at will.

50. 42. In a phonograph, mechanism for automatically reproducing a series of records including a record rotating table and means for successively supplying records thereto and discharging the same therefrom upon reproduction, a magazine adapted to receive the discharged records in substantially upright position therein, and controlling means responsive to a full magazine and operated by the last record delivered to said magazine for automatically stopping said reproducing mechanism.

43. In a phonograph, mechanism for automatically reproducing a series of records including a record rotating table and means for successively supplying records thereto and discharging the same therefrom upon reproduction, a magazine adapted to receive the discharged records in substantially upright position therein, and controlling means responsive to a full magazine and operated by the last record delivered to said magazine for automatically stopping said reproducing mechanism, said magazine being so disposed that said records are dropped in the same one against the other by said discharging mechanism and said controlling mechanism being so disposed as

to be engaged and actuated by the edge of said last record.

44. In a phonograph, mechanism for automatically reproducing a series of records including a reproducer, record rotating means, a magazine adapted to receive records to be reproduced, means for presenting said records successively to said reproducer to be reproduced and discharging the reproduced records, and a second magazine adapted to receive the reproduced records in substantially upright position therein, and means governed by the last record receivable in said second magazine when said magazine is full for controlling the operation of said reproducing mechanism.

15 45. In a phonograph, automatic record reproducing mechanism including a record rotating table and means for discharging reproduced records therefrom, a magazine adapted to receive reproduced records from said table, and controlling mechanism for said reproducing mechanism having a control member adjacent said magazine and engaged by a record therein for controlling the stopping and starting of said reproducing mechanism and movable to mechanism stopping position by a record discharged into said magazine when a predetermined number of records have been discharged thereinto.

30 46. In a phonograph, automatic record reproducing mechanism including a record rotating table and means for discharging reproduced records therefrom, a motor for rotating said table, control means for said motor, a magazine adapted to receive reproduced records from said table, and means associated with said magazine governing 35 said motor control means including a member located adjacent said magazine in position to be engaged by a record discharged thereinto when a predetermined number of records have accumulated in said magazine.

40 47. In a phonograph, automatic record reproducing mechanism including a rotatable table and means for discharging reproduced records therefrom, a magazine into which the reproduced records are discharged from said table, and controlling mechanism for said reproducing mechanism having a control member controlling 45 the stopping and starting of said reproducing mechanism and automatically movable to stopping position by the records in said magazine, 50 said control member being located in a position adjacent said magazine and having a projection engageable by a record discharged into said magazine when said magazine is full.

48. In a phonograph, mechanism for automatically reproducing a series of records including a record rotating table, a motor for operating said table, means also operated by said motor for supplying records to said table and discharging reproduced records therefrom, a magazine adapted to receive reproduced records from said table, manually operative means for controlling the operation of said motor, and automatic controlling mechanism having means for automatically moving said manual control means 65 into reproducing mechanism stopping position when a predetermined number of records have accumulated in said magazine.

49. In a phonograph, mechanism for automatically reproducing records including a record rotating table, a record receiving magazine, means for feeding a record therebetween, and means for discharging a record from said table following reproduction, an electric motor for constantly rotating said table, and means controlling the ener- 75

gization of said motor and starting the automatic operation of said feeding means including a switch operative by a record to close said motor circuit in response to the insertion of a record in said magazine.

50. In a phonograph, mechanism for automatically reproducing a record including a record rotating table, a record receiving magazine adapted to receive records of different diameter, and means for feeding records therebetween, an electric motor for rotating said table continuously throughout the operation of the phonograph, and means for setting said mechanism in operation automatically to play a record inserted in said magazine including a switch operative to close said motor circuit in response to the insertion of said record in said magazine irrespective of the diameter of the record.

51. In a phonograph, mechanism for automatically reproducing records including record receiving means adapted to receive large and small diameter records, an electric motor for actuating said mechanism, and means controlling the energization of said motor including a switch and a switch operating member therefor having two contact closed positions and a contact open position and movable from a normal switch open position into one or the other switch closed positions thereof in response to the insertion of a large or small diameter record in said magazine.

52. In a phonograph, mechanism for automatically reproducing records including a record rotating table, a record receiving magazine adapted to receive large and small diameter records, and means for feeding records therebetween, an electric motor for actuating said mechanism, means controlling the energization of said motor and effecting the automatic operation of said feeding means by the insertion of a record in said magazine to reproduce all the records in the latter including a switch having co-operating stationary and movable contact members, and a control member associated with said magazine and operated by the insertion of either a large or small record therein to close said contact members to initiate the automatic operation of said mechanism.

53. In a phonograph, mechanism for automatically reproducing records including a record rotating table and a record receiving magazine adapted to receive large and small diameter records, an electric motor for actuating said mechanism, means controlling the energization of said motor including a switch having co-operating stationary and movable contact members and a control member, said switch having two circuit closed positions of its co-operating contact members, into one of which positions it is moved by said control member in response to the insertion of a small diameter record and into the other of which it is moved by the insertion of a large diameter record.

54. In a phonograph, mechanism for automatically reproducing records including a record rotating table and a record receiving magazine adapted to receive large and small diameter records, an electric motor for actuating said mechanism, means for energizing said motor constantly throughout the operation of the phonograph including a switch having co-operating stationary and movable contact members and a control member, said control member being normally biased into a position corresponding to the circuit open position of said contact members, and said control member being movable in response

to the insertion of either a large or a small diameter record into a circuit closed position of said contact members.

55. In a phonograph, mechanism for automatically reproducing a series of records including a record rotating means and means for discharging a reproduced record therefrom, an electric motor for actuating said mechanism, a magazine adapted to receive the reproduced records discharged from said rotating means, a switch in the circuit of said motor, and means engaged and actuated by a record discharged into said magazine controlling said switch.

56. In a photograph, mechanism for automatically reproducing a series of records including a record rotating means and means for discharging a reproduced record therefrom, an electric motor for actuating said mechanism, a magazine adapted to receive the reproduced records discharged from said means, and a switch associated with said magazine controlling the energization of said motor in response to the accumulation in said magazine of a pre-determined number of records and having a switch controlling member in said magazine engaged by the edge of the last record.

57. In a phonograph, mechanism for automatically reproducing a series of records including a record rotating means, a motor for rotating said means having an energizing circuit, a magazine adapted to receive records to be reproduced, a second magazine adapted to receive the reproduced records from said rotating means, an electric switch associated with said first mentioned magazine for controlling the energization of said motor circuit in response to the insertion of a record therein, and a switch associated with said second mentioned magazine also controlling said motor circuit in response to the discharge of a record thereinto when said magazine is full.

58. In a phonograph, a record rotating means rotatable on a vertical axis, and mechanism for delivering a record in horizontal and centered position on said means while the latter is rotating on said axis including record delivery means from which the record is adapted to be extracted by a horizontal movement of the record, said record rotating means having eccentric means co-operating with the record to be centered thereon for imparting a record extracting horizontal movement to the record prior to centering the same on the table.

59. In a phonograph, a record rotating means rotatable on a vertical axis, and mechanism for delivering a record in horizontal and centered position on said means while the latter is rotating on said axis including record delivery means from which the record is adapted to be extracted by a horizontal movement of the record, and means eccentric from and associated with said record rotating means having a camming engagement with said record for imparting a horizontal movement thereto.

60. In a phonograph, a record rotating means rotatable on a vertical axis, a record magazine having means for receiving records in a substantially upright position therein and mechanism for delivering records in said magazine on said record rotating means while the latter is rotating including record delivery means from which the record is adapted to be extracted by a horizontal movement of the record, and eccentric cam means on the axis of said record rotating means for imparting said horizontal movement to the record.

61. In a phonograph, a record rotating table rotatable on a vertical axis and having an axial record centering member upstanding thereon, mechanism for delivering a record in horizontal 5 and centered position on said table including record delivery means having a horizontally directed record supporting opening, and means to extract said record from said opening prior to centering the record on the table including an eccentric projection on the record centering member by which a horizontal movement is imparted to the record prior to its deposit on the table.
62. In a phonograph, a record rotating table rotatable on a vertical axis, and an axial record 10 centering pin upstanding from the table adapted to receive the central aperture of a record, said centering pin having a concentric record centering portion adjacent the table and an eccentric and tapered terminal portion above said concentric portion.
63. In a phonograph, a record rotating table rotatable on a vertical axis, an axial record centering pin upstanding from the table, and means for feeding records laterally over said pin and 15 into centered position thereon in which said pin is received in a central aperture in the record, said means including a record supporting member having a groove in which said record is supported and said pin having eccentric means above 20 its record centering portion for imparting a horizontal movement to the record in said groove by the rotation of the pin prior to the deposit of the record on the table.
64. In phonograph, mechanism for automatically reproducing a series of records including a record rotating table rotatable on a vertical axis and a magazine for supplying records to said table in a generally horizontal position of the record, said magazine including a plurality of record 25 supporting members having openings in which the records are supported, and means to extract said records horizontally from said openings by the rotation of said table prior to centering the records on said table including a record centering 30 pin upstanding above the table having a tapered end portion which is eccentric to the rotating table.
65. In a phonograph, mechanism for automatically reproducing a series of records including a record rotating table, means for presenting records of the same or different diameter for successive reproduction on said table, reproducer mechanism including an oscillating reproducer 35 successively reproducing records on said table, and means actuated by said reproducer while the latter is moving in the same direction for successively supplying new records to said table, and mechanical means for successively automatically controlling said first mentioned mechanism to effect 40 complete automatic reproduction of successive records irrespective of whether the latter have eccentric or spiral terminal grooves engaged by said reproducer and returning said reproducer into position to initiate reproduction of a new record of the same or different diameter.
66. In a phonograph, mechanism for automatically reproducing a series of records including a record rotating table, means for presenting records of the same or different diameter for successive reproduction on said table, reproducer mechanism including an oscillating reproducer 45 successively reproducing records on said table, and means for successively supplying new records to said table, and mechanical means actuated by said reproducer while the latter is moving in the same direction for successively automatically controlling said first mentioned mechanism to effect complete automatic reproduction of successive records irrespective of whether the latter have eccentric or spiral terminal grooves engaged by said reproducer and returning said reproducer into position to initiate reproduction of a new record of the same or different diameter.
67. In a phonograph, a record rotating table, reproducer mechanism including an oscillating reproducer for successively reproducing a series of records thereon, means for successively discharging reproduced records from said table and presenting a new record for reproduction thereon, and mechanical means actuated by said reproducer while the same is moving in the same direction for automatically controlling said mechanism to effect complete automatic reproduction 10 of successive new records following reproduction of a record having terminal grooves of either the eccentric or spiral grooved type engaged by said reproducer.
68. In a phonograph, a record rotating table, 15 reproducer mechanism including an oscillating reproducer for successively reproducing a series of records thereon, means for successively discharging reproduced records from said table and successively supplying new records onto said table, and means actuated by said reproducer while the same is moving in an inward direction and is at different distances from the table axis for automatically controlling said mechanism to effect automatic operation on successive new records 20 following reproduction of a record having terminal grooves of either the eccentric or spiral grooved type engaged by said reproducer.
69. In a phonograph, a record rotating table, 25 reproducer mechanism including an oscillating reproducer for reproducing records thereon, means for successively supplying records of the same or different diameter to said table, and means actuated by said reproducer while the latter is moving in the same direction and is at 30 different distances from the table axis for automatically controlling said mechanism to effect automatic operation on successive new records following reproduction of a record having terminal grooves of either the eccentric or spiral grooved type engaged by said reproducer.
70. In a phonograph, a record rotating table, 35 reproducer mechanism including an oscillating reproducer for reproducing records thereon, means including a magazine for successively supplying records of the same or different diameter to 40 said table, means for automatically controlling said mechanism to effect automatic operation on successive new records following reproduction of a record having terminal grooves of either the eccentric or spiral grooved type engaged by said reproducer irrespective of variations in diameter and returning said reproducer into position to initiate reproduction of a new record irrespective of the diameter of the record.
71. In a phonograph, a record rotating table, 45 reproducer mechanism including an oscillating reproducer for reproducing records thereon, means including a magazine for successively supplying records of the same or different diameter to 50 said table, means for automatically controlling said mechanism to effect automatic operation on successive new records following reproduction of a record having terminal grooves of either the eccentric or spiral grooved type engaged by said reproducer irrespective of variations in diameter and returning said reproducer into position to initiate reproduction of a new record irrespective of the diameter of the record.
72. In a phonograph, a record rotating table, 55 reproducer mechanism including an oscillating reproducer for reproducing records thereon, means including a magazine for successively supplying records of the same or different diameter to 60 said table, means for automatically controlling said mechanism to effect automatic operation on successive new records following reproduction of a record having terminal grooves of either the eccentric or spiral grooved type engaged by said reproducer irrespective of variations in diameter and returning said reproducer into position to initiate reproduction of a new record irrespective of the diameter of the record.
73. In a phonograph, a record rotating table, 65 reproducer mechanism including an oscillating reproducer for reproducing records thereon, means including a magazine for successively supplying records of the same or different diameter to 70 said table, means for automatically controlling said mechanism to effect automatic operation on successive new records following reproduction of a record having terminal grooves of either the eccentric or spiral grooved type engaged by said reproducer irrespective of variations in diameter and returning said reproducer into position to initiate reproduction of a new record irrespective of the diameter of the record.
74. In a phonograph, a record rotating table, 75 reproducer mechanism including an oscillating reproducer for reproducing records thereon, means including a magazine for successively supplying records of the same or different diameter to 80 said table, means for automatically controlling said mechanism to effect automatic operation on successive new records following reproduction of a record having terminal grooves of either the eccentric or spiral grooved type engaged by said reproducer irrespective of variations in diameter and returning said reproducer into position to initiate reproduction of a new record irrespective of the diameter of the record.

5 said mechanism to effect automatic operation on successive new records following reproduction of a record having terminal grooves of either the eccentric or spiral grooved type engaged by said reproducer irrespective of variations in diameter, means for automatically starting the phonograph in operation upon the insertion of a record in said magazine, and means for automatically stopping said reproducing mechanism upon the reproduction of the last record inserted in said magazine.

10 72. In a phonograph, mechanism for automatically reproducing a series of records of the type having an inner eccentric needle groove including a record rotating table and a swinging reproducer mechanism having at its free end a reproducer adapted to traverse the playing groove inward from the record periphery into the eccentric groove in said record, tripping means operated by 15 the inward movement of said reproducer mechanism upon the reproduction of a record to return said reproducer mechanism, and means responsive to repeated inward movements of said reproducer mechanism as said reproducer transverses said eccentric groove for advancing said tripping means in a step by step manner into tripping position with successive revolutions of the record.

15 73. In a phonograph, mechanism for automatically reproducing a series of records of the type having an inner eccentric needle groove including a record rotating table and a swinging reproducer mechanism having at its free end a reproducer adapted to traverse the playing groove inward from the periphery into the central eccentric groove of a record on the table, means to return said reproducer mechanism upon reproduction of a record including means normally holding the same from operation, and means to trip the latter by the inward movement of said reproducer mechanism while said reproducer is transversing said eccentric groove including means for advancing said tripping means to tripping position in a progressive manner during successive inward movements of said reproducer.

20 74. In a phonograph, mechanism for automatically reproducing a series of records including a record rotating table and a swinging reproducer mechanism adapted to swing in one direction during reproduction of the record on the table, power operated mechanism for constantly rotating said table, mechanism adapted automatically to return said reproducer mechanism following the reproduction of a record including a cam member, mechanism for controlling the operation of said cam member including a dog carried thereby and biased into engagement with a constantly rotating part of said power operated mechanism, an abutment means normally engaging said dog and holding the same in disengaged position against its bias, and means acting on said cam member to urge the same for rotation independently of said rotating part during engagement of said dog with said abutment means.

25 75. In a phonograph, mechanism for automatically reproducing a series of records, including a record rotating table and a swinging reproducer mechanism adapted to swing in one direction during reproduction of the record on the table, power operated mechanism for constantly rotating said table, mechanism adapted automatically to return said reproducer mechanism following the reproduction of a record including a cam member, mechanism for controlling the operation of said cam member including a dog carried thereby and biased into engagement with a constantly

30 rotating part of said power operated mechanism, an abutment means normally engaging said dog and holding the same in disengaged position against its bias, and means acting on said cam member to urge the same for rotation independently of said rotating part during engagement of said dog with said abutment means comprising a cam on said drum having an abrupt working face and a stationarily supported cam follower acting on said face during the engagement of said dog and abutment means to move said dog out of driving engagement and hold the same against its bias during reproduction of a record.

35 76. In a phonograph, a swinging reproducer arm, power operated mechanism for returning said arm toward initial position following a record reproducing movement thereof, a member controlling the operation of said mechanism, and means for actuating said control member to effect the operation of said mechanism by the movement 20 of said arm following reproduction of a record irrespective of whether the terminal grooves in the latter are eccentric or spiral and including co-operating pawl and ratchet means carried by said reproducer arm and said control member operative following reproduction of a record having an eccentric terminal groove for advancing said control member in a step by step manner into a position to effect operation of said mechanism, and cooperating means cooperating automatically 25 with said control member following reproduction of a record having a spiral terminal groove.

40 77. In a phonograph, an oscillating reproducer arm movable inward during reproduction and reversely to return to cooperate with a new record, power operated mechanism for returning said arm following a record reproducing movement thereof, a member controlling the operation of said mechanism, and means for actuating said controlling member to effect the operation of said mechanism by repeated inward movements of said arm following reproduction of a record including cooperating pawl and ratchet means carried by said reproducer arm and said control member.

45 78. In a phonograph, a swinging reproducer arm, power operated mechanism for returning said arm toward initial position following a record reproducing movement thereof, a latch holding said mechanism from operation, and tripping means for said mechanism operative irrespective 50 of whether the terminal grooves in successive records are eccentric or spiral and including a horizontally extended ratchet carried by said latch, and a co-operating pawl carried by said arm in position to engage said rack and actuate 55 said latch in a step by step manner into mechanism tripping position following a record reproducing movement of said arm on a record having an eccentric terminal groove, and cooperating means for automatically rendering said ratchet 60 and pawl elements inoperative following reproduction of a record having a spiral terminal groove.

70 79. In a phonograph, an oscillating reproducer arm movable inward during reproduction and 65 reversely to return to cooperate with a new record, power operated mechanism for returning said arm following a record reproducing movement thereof, a latch holding said mechanism from operation, and tripping means for said mechanism including a ratchet carried by said latch and a cooperating pawl carried by said arm in position to engage said rack and actuate said latch upon an inward movement of said arm following a record reproducing movement of the latter.

80. In a phonograph, a swinging reproducer arm, power operated mechanism for returning said arm following the record reproducing movement thereof, a latch normally holding said mechanism from operation, a laterally extended rack carried by said latch, a pawl carried by said arm in position to co-operate with said rack, and means carried by said pawl normally biased into a position to shield said pawl against effective engagement with said rack and inoperative after a reverse movement of said arm.
81. In a phonograph, automatic mechanism for reproducing records of the type having either spiral or eccentric inner needle grooves including a record rotating table, means for presenting successive records of the same or different diameter thereon, and a swinging reproducer arm carrying a reproducer cooperating with said successive records, power operated mechanism for returning said arm following a record reproducing movement thereof into position to initiate reproduction of a new record of the same or different diameter, a control member normally holding said mechanism from operation, and means for operating said member to effect operation of said mechanism which is responsive to the inward movement of said reproducer arm while the reproducer is within and under the action of the inner grooves of either of said records.
82. In a phonograph, a record rotating table, a swinging reproducer mechanism including a reproducer adapted to traverse the playing groove of a record on said table, power actuated mechanism for returning said reproducer mechanism to initial playing position on a new record of the same or different diameter after a record reproducing movement thereof, means for controlling said power actuated mechanism including a control member normally biased into a position in which said power actuated mechanism is restrained from returning said reproducer mechanism, and means for automatically controlling said controlling member for automatic operation on successive records having spiral or eccentric terminal grooves including an abutment member interposed between said control member and reproducer mechanism for tripping said control member and adjustable to vary the distance between said members at which tripping engagement therebetween takes place.
83. In a phonograph, a horizontal record rotating table, a laterally swinging reproducer mechanism including a reproducer adapted to traverse the playing groove of a record on said table, power actuated mechanism for returning said reproducer to initial playing position on a new record of the same or different diameter after a record reproducing movement thereof, controlling means including a latch biased into a position in which it restrains said power actuated mechanism from operation to return said reproducer and from which it is moved by said reproducer mechanism following reproduction of a record, and means for automatically controlling said controlling member for automatic operation on successive records having spiral or eccentric terminal grooves including laterally adjustable abutment means interposed between said reproducer mechanism and latch for varying the point in the inward swing of said reproducer mechanism at which tripping of said latch will take place.
84. In a phonograph, a record rotating table, reproducer mechanism including a swinging reproducer adapted to traverse the playing groove of a record on said table, power actuated mechanism for returning said reproducer to initial playing position following a record reproducing movement thereof, a control member constantly biased into a mechanism controlling position in which it restrains said power actuated mechanism from returning said reproducer and from which it is moved by the reproducer mechanism following reproduction of a record, and co-operating ratchet and pawl mechanism carried by said reproducer mechanism and control member for advancing the latter in a step by step movement in a tripping direction by the record reproducing movement of said reproducer.
85. In a phonograph, a record rotating table, reproducer mechanism including a swinging reproducer adapted to traverse the playing groove of a record on said table, power actuated mechanism for returning said reproducer to initial playing position following a record reproducing movement thereof, a control member constantly biased into a mechanism controlling position in which it restrains said power actuated mechanism from returning said reproducer and from which it is moved by the reproducer mechanism following reproduction of a record irrespective of whether the terminal grooves in the latter are eccentric or spiral, a laterally extended ratchet carried by said control member, and a pawl carried by said reproducer mechanism in position to co-operate with said ratchet to move said control member progressively in a step by step manner away from mechanism controlling position following the record reproducing movement of said reproducer on a record having an eccentric terminal groove.
86. In a phonograph, mechanism for automatically reproducing records of the type having an inwardly directed spiral playing groove terminating in an inner eccentric tripping groove, said mechanism including a record rotating table, reproducer mechanism including a swinging reproducer adapted to traverse said spiral groove inward into said eccentric groove, power actuated mechanism for returning said reproducer to its initial playing position following a record reproducing movement thereof, a latch normally restraining said power actuated mechanism from operation, a rack carried by said latch and extended laterally toward said reproducer, a co-operating pawl carried by said reproducer mechanism, and means to actuate said latch by the repeated inward movement of said pawl only after the first reverse movement of said reproducer under the direction of said eccentric groove.
87. In a phonograph, mechanism for automatically reproducing records of the type having an inwardly directed spiral playing groove terminating in an inner eccentric tripping groove, said mechanism including a record rotating table, reproducer mechanism including a swinging reproducer adapted to traverse said spiral groove into said eccentric groove, power actuated mechanism for returning said reproducer to its initial playing position following a record reproducing movement thereof, a latch normally restraining said power actuated mechanism from operation, a rack carried by said latch and extended laterally toward said reproducer, a co-operating pawl carried by said reproducer mechanism, means for shielding said pawl from operative engagement with said rack during the initial inward movement of said pawl thereover and thereafter permitting said pawl to engage said ratchet and advance said latch toward mechanism tripping position.

- sition upon each oscillation of said reproducer under the direction of said eccentric groove.
88. In a phonograph, reproducer tripping mechanism including a swinging reproducer, a constantly rotating power driven member, a cam for returning said reproducer following a record reproducing movement thereof, means for establishing a driving connection between said power driven member and cam including a dog carried by said cam having a latch engaging extension, means normally biasing said dog into driving engagement, a latch normally engaging said extension and holding said dog against its bias, means for effecting a step by step advance of said latch to tripping position by repeated oscillations of said reproducer by the action of said eccentric groove including co-operating pawl and ratchet mechanism carried by said latch and reproducer mechanism, and means for holding said
- latch against reverse movement between successive latch advancing steps.
89. In a reproducer controlling mechanism, a horizontally extended pawl having a rack engaging tooth, and a tooth shielding member carried by the free end of said pawl and normally biased into tooth shielding position.
90. In a reproducer controlling mechanism, a horizontally extended rack, a co-operating horizontally extended pawl having a rack engaging tooth at its free end, and a tooth shielding member carried by the free end of said pawl having a pin and slot connection therewith, said member being normally biased into a position in which said slot is vertically disposed and a portion of said member is interposed between the teeth of said rack and the tooth of said pawl.

CLEMMA R. RANEY.

CERTIFICATE OF CORRECTION.

Patent No. 2,029,191.

January 28, 1936.

CLEMMA R. RANEY.

It is hereby certified that error appears in the printed specification of the above numbered patent requiring correction as follows: Page 3, second column, line 75, after "opening" insert a comma; page 8, second column, line 66, claim 6, after "magazine" insert a comma; line 72-73, claim 7, for "vertically" read vertical; page 10, first column, line 7, claim 20, for "indicate" read initiate; line 8, same claim, for "their" read record; page 13, second column, line 14, claim 56, for "photograph" read phonograph; page 14, first column, line 34, claim 64, after "In" insert the article a; and that the said Letters Patent should be read with these corrections therein that the same may conform to the record of the case in the Patent Office.

Signed and sealed this 28th day of April, A. D. 1936.
